UNITED STATES PATENT OFFICE

107,166

DESIGN FOR A WRINGER HEAD

Howard Witmer, Newton, Iowa, assignor to One Minute Washer Company, Newton, Iowa, a corporation of Iowa

Application April 17, 1937, Serial No. 68,839

Term of patent 7 years

To all whom it may concern:

Be it known that I, Howard Witmer, a citizen of the United States and a resident of Newton, in the county of Jasper and State of Iowa, have invented a certain new, original, and ornamental Design for a Wringer Head, of which the following is a specification, reference being had to the accompanying drawing, forming part thereof:

Figure 1 is a top or plan view of a wringer
head embodying my new design.

Figure 3 is a front elevation thereof.

I claim:

The ornamental design for a wringer head as shown.

HOWARD WITMER.
